UNITED STATES PATENT OFFICE.

ALFONSO P. BALLERINO, OF HOLLYWOOD, CALIFORNIA, ASSIGNOR OF ONE-HALF TO
MALCOLM C. NASON, OF HOLLYWOOD, CALIFORNIA.

FOOT-OPERATED THROTTLE-CONTROL APPARATUS.

1,335,314.

Specification of Letters Patent. Patented Mar. 30, 1920.

Application filed July 7, 1919. Serial No. 309,159.

To all whom it may concern:

Be it known that I, ALFONSO P. BALLERINO, a citizen of the United States, residing at Hollywood, in the county of Los Angeles and State of California, have invented a new and useful Foot-Operated Throttle-Control Apparatus, of which the following is a specification.

This invention pertains to an apparatus 10 for regulating the degree of opening of the throttle valve and is especially useful as an attachment to automobiles of the type not provided with a foot-operated throttle by the manufacturers of said automobiles.

15 An object of the invention is to produce a device of this character which is comparatively inexpensive to manufacture.

Another object is to so construct the apparatus that it may be readily installed by 20 the operator of the car without the need of the services of an experienced mechanic.

Another object is to so construct the apparatus that it will work entirely independent of the hand-operated throttle control 25 mechanism so that both hand and foot operation can be effected independently of each other.

Other objects and advantages will appear in the subjoined detailed description.

30 The accompanying drawings illustrate the invention:

Figure 1 is a plan view of the invention installed in an automobile which is fragmentarily shown.

35 Fig. 2 is an enlarged plan view of the invention, the throttle arm and connecting rod of the hand-control mechanism being fragmentarily shown.

Fig. 3 is a front elevation of Fig. 2.

40 Fig. 4 is a sectional elevation on line indicated by x^4-x^4 , Fig. 2.

Fig. 5 is an enlarged detail partly in section on line indicated by x^5-x^5 , Fig. 2.

Fig. 6 is a plan detail partly in section on 45 line indicated by x^6-x^6 , Fig. 5.

Fig. 7 is a perspective view of the slotted member which is connected with the throttle arm.

An automobile is fragmentarily indicated 50 at a in Fig. 1, the motor being indicated at b . The engine b is furnished with explosive charges by a carburetor indicated at c , said carburetor having a throttle arm d whereby the degree of suction on the carburetor is

regulated in a manner well understood in 55 the art pertaining to carburetors.

The outer end of the throttle arm d is provided with a bolt 1 having a nut 2. The bolt 1 passes through a flange 3 of a slotted member 4, the slot being indicated at 5 and said slot being curved as clearly shown in Fig. 7. In the instance shown in the drawings the slotted member 4, exclusive of the flange 3, is of rectangular construction in cross section and the flange 3 projects laterally from 60 near the bottom edge of the side 6 of said member. The slot 5 is positioned in the top 7 of the member 4. The bolt 1 passes through a hole 8 in the flange 3. Between the flange 3 and the head of the bolt 1 is a 70 spring lock washer 9 and also between the arm d and nut 2 is a spring lock washer 10. The slot 5 is adapted to receive the downwardly bent end e of a connecting rod f which forms a portion of the hand throttle- 75 control mechanism indicated in general by the character g . The downwardly bent end e is provided beneath the top 7 with a pin 11 to prevent the connecting rod f from becoming disengaged from the member 4.

80 The flange 3 is provided with another hole 12 to receive the downwardly bent end 13 of a push rod 14 which is provided with a horizontally bent end 15 that has a reduced portion 16 forming a pivot extending through a hole or slot 17 in one end of one of the members 18 of a foot-operated lever. The foot-operated lever comprises, besides the member 18, a second member 19 bent at right angles in plan from the member 18. 85 The member 19 is also bent at an angle from the member 18 in elevation. The free end of the member 19 terminates in a flange 20 adapted for engagement by the operator's 90 shoe.

95 The lever 18, 19 is pivotally mounted on the engine b by a bracket 21 which, if desired, may be formed of sheet metal. The bracket 21 comprises a more or less U-shaped member 22 and a flange 23 extending at right angles to the U-shaped member 22. The U-shaped member 22 is provided with holes 24, 25 to receive the lever member 18 which thus journals or pivots said lever. The outer end of the flange 23 is provided with a hole 26 to receive a bolt 27 which is screw-threaded into the cylinder head h of the engine. The bolt 27 may be one of the

bolts employed in fastening the cylinder head in place.

The flange 3 is provided with another hole 28 in which is fastened one end of a coil 5 spring 29 that is connected at its other end by a connection member 30 to the chassis *k* of the automobile.

The outer end of the bent portion 15 of the rod 14 forms an elongated head 31 which 10 can be slipped in and out of the slot 17 when the head 31 is turned to aline lengthwise with the slot 17. After the parts are assembled as in the drawings, the head 31 is positioned crosswise of the longitudinal axis 15 of the slot 17 so that the rods 14, 18 will not become accidentally separated.

In practice, the invention operates as follows: If the operator desires to use the hand-operated throttle mechanism he may 20 do so, thus causing shifting of the connecting rod *f*. When he wishes to open the throttle valve wider the rod *f* will be shifted in the direction of the arrow *m*, Fig. 2, so as to move the member 4 against the pull of 25 the spring 29, thus moving the throttle arm *d*. When he causes the rod *f* to be shifted in the opposite direction the spring 29 will retract the member 4 and thus cause retraction of the throttle arm *d*.

30 When the operator desired to open the throttle valve wider by use of his foot, he will depress the flange 20 thus pushing the rod 14 toward the right in Fig. 2 as indicated by the arrow *n*, causing the throttle 35 arm *d* to be moved in the same direction as when the rod *f* is shifted in the direction of the arrow *m* as above described. However, this shifting of the rod 14 will not move the rod *f* since the slot 5 will allow the member 40 4 to move without any effect on the rod *f*.

When the operator desires to reduce the opening of the throttle valve he releases the pressure of his foot on the flange 20 and thereupon the spring 29 retracts the member 4 to cause retraction of the throttle arm *d*. 45

The invention is not limited to the exact details of construction shown in the drawings and described above but includes such changes and modifications as may lie within the spirit and scope of the appended claim. 50

I claim:

The combination with a throttle arm, of a member rectangular in cross-section provided near the bottom edge of one side thereof with a laterally projecting flange, 55 the top of said member having a slot to receive one end of a connecting rod of a hand control throttle mechanism, there being an opening between the top and the flange, a push rod pivotally connected with the flange and having a bent end provided with a head, 60 said push rod passing through said opening, a spring fastened at one end to the flange to return the rectangular member to normal position, a foot-operated lever having a 65 member bent at right angles to another member of said lever in two different planes extending at right angles to each other, one of the lever members being provided with a slot to receive the bent end of the push rod, 70 and means to fasten the flange to the throttle arm.

Signed at Los Angeles, California, this 30th day of June 1919.

ALFONSO P. BALLERINO.
